Benjamin J. Rothmann
ATTORNEY

UNITED STATES PATENT OFFICE.

CHARLES ROTHMANN, OF CLOSTER, NEW JERSEY.

ROADWAY WITH IMPROVED CURBSTONE AND GUTTER.

Application filed July 12, 1928. Serial No. 292,169.

This invention relates to roadways, and particularly to curbstone and gutter portions of roadways. Heretofore, roadways have been frequently built with curbstones 5 to separate the soil from the road, and often gutters have been built adjacent to the curbstone and between it and the roadway proper for bettering the drainage of the highway. These curbstones and gutters 10 were preferably made out of concrete, cement, or similar forming and hardening materials, which were poured in place directly at the roadway, the method necessitating first forming the curbstone at the road 15 and permitting it to set, then forming the gutterway adjacent to the curbstone and permitting it to set, and finally completing the roadway between the opposite gutters after they have thus set, all of which consumed 20 much time, interruption, and undue expense.

The principal object of my invention is to remedy the above mentioned disadvantages, and to provide a fabricated unit of curbstone having integrally therewith a cooperat- 25 ing or corresponding section of road gutter, both of which sections are cast out of a single mold and in a single operation at the manufacturing plant.

In carrying out the invention a mold is 30 provided which is capable of being worked with the usual molding machinery, and the mold is so configured that it will cast out of the same run of material and in the same operation the unit comprising the curbstone 35 section and concomitant section of gutter.

Other objects and advantages will hereinafter appear.

In the accompanying drawings,—

Fig. 1 is a perspective view of the curbstone section and concomitant gutter section, constituting the article of manufacture 40 of this invention.

Fig. 2 is a cross section and perspective view of the improved roadway, and shows 45 the fabricated curbstone and gutter units of this invention, as they appear when laid in the roadway.

The article or block of the invention, comprises a thick horizontal member 1 of elongated polygonal formation in plan, and a thick vertical member 2 formed integrally with an extending transversely of and upwardly from the inner end portion of the horizontal member. The member 2 and the 55 underlying or inner end portion of the horizontal member 1 constitute the curb portion

of the block, and that part 3 of the horizontal member 1, which is located outwardly beyond the curb portion, constitutes the gutter portion of the block. The curb portion 2 60 gradually increases in thickness outwardly from a point slightly above the gutter portion 3 to said portion so as to reinforce the portions at their point of juncture. This thickened portion 4 of the curb portion 2 is 65 concave to effect a better drainage and clearing of the gutter. In manufacturing this article a mold is prepared which may be utilized with any suitable molding machine for casting the article out of one run of 70 material in a single molding operation, after which the article may be baked in any suitable manner. Any suitable cementitious material which will serve the desired purpose may be utilized for the making of this article. 75

After the articles 1 have been manufactured they may be put into the roadway 5 in the manner shown in Fig. 2, to thus constitute the completed curbstone 6 and gutter 7 80 of the roadway.

The articles or blocks are of elongated polygonal formation in plan, and are arranged with their longitudinal axes at right angles to the axis of the roadway. As the 85 gutter portions are thick and extend transversely of the roadway, such portions will not crack, break or crush under the weight of any vehicle passing thereover or resting thereon. Furthermore, this formation of 90 the blocks permits them to be laid in a comparatively short time and with comparatively little labor and expense. As the curb portions of the blocks are thick and due to their increased thickness above and below 95 their line of juncture with the gutter portions, the curb portions will not crush, crack or break under any strain to which they may be subjected as the result of a vehicle backing against them or passing over them. The blocks are comparatively narrow, durable, strong and practically indestructible. As the articles 1 are made sufficiently narrow they may be readily laid 100 to follow any curvature, bend, or curved grade of the roadway 5. Due to the articles 1 being fabricated at the manufacturing plant with proper machinery, available processes, and desirable materials, the produced curbstone and gutter of this roadway 105 is superior to those built heretofore by pouring material directly into the roadway, and 110

as the articles 1 can be put in place conveniently and rapidly it results in an economical, well appearing, strong, durable, efficient, and improved curbstone and gutter for the roadway.

Variations may be resorted to within the scope of the invention, and portions of the improvements may be used without others.

Having thus described my invention, I claim:—

As an article of manufacture, a portable curb and gutter forming block, made from concrete and having a thick horizontal member of elongated polygonal formation in plan and adapted to be laid with its longi-

tudinal axis angularly of the axis of the roadway, and a thick vertical member formed integrally with and extending transversely of and upwardly from the inner end portion of the horizontal member, and the vertical member increasing outwardly in thickness from a point slightly above the horizontal member to said member so as to reinforce the members along their line of juncture.

Signed at New York, in the county of New York and State of New York, this 11th day of July, A. D. 1928.

CHARLES ROTHMANN.
